UNITED STATES PATENT OFFICE.

STUART BALLANTINE, OF WHITE HAVEN, PENNSYLVANIA, ASSIGNOR TO ELECTRICAL RESEARCH LABORATORIES, INC., OF CHICAGO, ILLINOIS, A CORPORATION OF DELAWARE.

DESIGN FOR AN ESCUTCHEON PLATE FOR RADIORECEIVERS.

Application filed August 19, 1926. Serial No. 18,779. Term of patent 3½ years.

To all whom it may concern:

Be it known that I, STUART BALLANTINE, a citizen of the United States, and a resident of White Haven, in the county of Luzerne and State of Pennsylvania, have invented a new, original, and ornamental Design for an Escutcheon Plate for Radioreceivers, of which the following is a specification, reference being had to the accompanying drawing, which forms a part thereof.

In the drawing:—

The figure is a plan view of an escutcheon plate showing my new design.

I claim:

The ornamental design for an escutcheon plate for radioreceivers, as shown.

STUART BALLANTINE.
